UNITED STATES PATENT OFFICE.

WILLIAM WESTBURY, OF CANEY, KANSAS, ASSIGNEE TO LAURA ANNA WESTBURY,
OF INDEPENDENCE, KANSAS.

REGENERATIVE GLASS FURNACE.

Application filed December 27, 1922. Serial No. 609,258.

This invention relates to glass melting tanks or furnaces of the regenerative type, in which, as commonly constructed, series of flues, each containing a gas burner, are provided at each side of the furnace, these series of flues at each side communicating through checker chambers with a tunnel, which tunnels connect at their rear ends through a valve chamber with a discharge stack. This valve chamber is provided with an air inlet and contains a so-called "butterfly" valve movable to two different positions so as to connect one tunnel with the stack and the other tunnel with the air inlet, or vice versa. By this means the burners in the flues at one side of the furnace may be set into operation, and connected with the air inlet and disconnected from the stack, for furnishing flames to sweep across the melting chamber toward the opposite set of flues, which will serve as outlets for the products of combustion and will be connected with the stack for the discharge of such products therethrough. This operation is "reversed" at regular periods, commonly every twenty minutes, the burners and regenerators at each side being alternately employed as furnace heaters and discharge devices, respectively, for the products of combustion. In the discharge of the products of combustion on the exhaust side, the checkers of the regenerators at such side are heated to keep the flues at a desired high temperature, as well as to heat the incoming air passing to the flues, for admixture with the fuel gas, when the heating action is reversed and said regenerators become a part of the agencies at the heating side. Ordinarily a valve is provided for each flue burner, for individually regulating the supply of gas thereto, but reliance is placed upon the single butterfly valve referred to as a means for controlling the flow of air to the working burners.

Furnaces of this type are open to serious working objections. In the first place, it is necessary to adjust the valves of the burners from time to time, to vary the amount of fuel supplied thereto and the spread and intensity of the flames supplied thereby, and this results in wide variations in the flow of the air to the flues, and lack of uniformity or lack of proper supply of air to the burners to properly support combustion.

When the flame from any one burner is cut

down and the air draft thereto is reduced, an excess amount of air passes to the other burners, and the air flow is so irregular in action, when the gas supply to the different burners is varied to different degrees, that it is difficult to keep the burners in proper operation to maintain the desired variations of temperature at different points in the furnace. Very often the furnace gets too hot at the working end, requiring the teaser to close the gas valve or valves of one or more front working burners, thus completely cutting off the flames at the working end, but this does not stop the flow of air passing through the associated checker chambers. This results in the corresponding checker chambers at the opposite side of the furnace being unduly cooled by the volume of relatively cool air passing therethrough, so that the glass at the adjacent side of the furnace becomes hard, causing lines or cords, termed chill cords. Any variation, in fact, in the volume of gas supplied to and the amount of flame projected from any burner results not only in the undue cooling of checkers at the opposite side of the furnace, and chilling of adjacent portions of glass in the melting chamber, but also in irregular and spasmodic flow of currents of air to the flues at the heating side, making it difficult and at times impossible to keep the furnace at the proper working temperature. The proper operation of furnaces of this kind, therefore, is to a large extent critical and in its conduct requires expert handling.

One object of my invention is to provide a novel construction of means for controlling communication between the furnace flues and the atmosphere and a stack, whereby the flow of air to the burners will be regulated, and whereby the air supply to a burner may be cut off or reduced without affecting the supply of air to another burner or burners.

A further object of the invention is to provide a construction of means for controlling communication between a burner flue and the stack and the source of air supply, whereby individual control for each burner flue is ensured, whereby uniformity of operation of the burners may be secured, and whereby chilling of the glass may be obviated and the noted objections to furnaces of ordinary construction overcome or reduced to the minimum.

With these and other objects in view, the

invention consists of a regenerative glass furnace embodying the features of construction, combination and arrangement of parts, hereinafter fully described and claimed and as shown in the accompanying drawings, in which:—

Figure 1 is a vertical transverse section through a regenerative furnace constructed in accordance with my invention.

Figure 2 is a top view of the same.

Figure 3 is a plan view of one of the valve or damper controlling and locking devices.

Figure 4 is a fragmentary top plan view of a modified form of furnace.

Figure 5 is a vertical transverse section thereof.

Referring now more particularly to the drawings, 1 designates the furnace body provided with the glass melting chamber 2 containing in its lower portion the body of glass 3 which is to be melted. Arranged at each side of the furnace is a series of individual regenerator chambers 4 containing the checkers 5 which may be of the ordinary or any preferred construction. Each chamber 4 communicates at its upper end through an upper horizontal flue 6 with the adjacent side of the melting chamber 2, and communicates at its base through a lower horizontal flue 7 with a tunnel 8. Any number of regenerators of this construction may be provided at each side of the furnace, the regenerators at the opposite sides being placed opposite or in alignment with each other. The tunnels 8 connected with the respective regenerators extend rearwardly and are in communication at their rear ends through a cross connection 9 with a stack 10. In accordance with my invention I do away with the usual valve chamber and butterfly valve provided at the junction point of the cross connection 9 with the stack 10.

In accordance with my invention, I also provide means for separately and individually connecting each flue 7 and its checker chamber with the atmosphere or a source of air supply and with the stack. As shown the upper wall of the flue 7 is provided with an air inlet opening 11 controlled by a hinged valve or damper 12, which when in open position provides for the passage of air through the associated flue 7 and checkers 5 to the flue 6. A vertically movable sliding valve or damper 13 is provided for controlling communication between the flue 7 and the tunnel 8, and this valve or damper 13 is arranged between the air inlet 11 and the tunnel 8. A cord, chain or cable 14 is connected at its ends to the respective valves or dampers 12 and 13 and is wound one or more times at its intermediate portion around a pulley or sheave 15 arranged at a suitable elevation above the top of the flue 7. The pulley 15 is mounted on a shaft 16 journaled in a bearing 17 upon

the end of a bracket 18 secured to the outer side wall of the checker chamber, and said shaft 16 is provided with a handle 19 or other suitable manipulating device whereby the pulley may be turned in one direction or the other for shifting the cable 14 for a valve or damper actuating operation. By turning the handle 19 in one direction the valve 12 will be opened and the valve 13 closed, and by turning said handle in the opposite direction a reverse motion of the valves will be secured, that is, the valve 13 will be opened and the valve 12 closed.

Arranged within each flue 6 is a gas burner 20 upon the end of a branch pipe 21 connected with a supply pipe 22. The supply pipe 22 has portions disposed at both sides of the furnace and connected with the burner pipes 21 for the supply of gas thereto, said pipe 22 being in communication with a main gas supply pipe 23, and a valve 24 being provided in each burner pipe 21 for individually controlling the flow of gas thereto. From this it will be seen that when the burners and regenerators at either side of the furnace are set into action for supplying flames to sweep across the furnace, the amount of gas supplied to the burners 20 at such side may be varied and the supply of gas to each burner governed as required to vary the size of the flame projected therefrom, or to entirely cut such burner out of action.

In order to adapt the valves 12 and 13 to be held locked in relatively open and closed positions, or such intermediate positions as may be desired, I provide suitable locking mechanism which may consist of a ratchet wheel 25 on the shaft 16 adapted to be engaged by a pawl or dog 26 on bracket 18.

When the burners associated with one series of regenerators are set into action, the valve controlling devices 19 used in conjunction therewith are operated to open the valves 12 and close the valves 13, while the valve operating devices used in conjunction with the opposite series of regenerators are manipulated to close the valves 12 and open the valves 13 thereof. Hence at the side of the furnace where the burners are in action, communication between the regenerators and the tunnel 8 will be cut off by the valves 13 while the air inlets 11 will be opened for supplying air to the burner flues 6, while at the opposite side of the furnace the air inlet valves will be completely closed and the valves 13 opened to allow the products of combustion to discharge through the regenerators at such side into the associated tunnel 8 and thence to the atmosphere through the stack 10. In reversing the fire the supply of gas to the burners of the regenerators which have been employed as heaters is cut off by closing the valves 24, the dampers 12 of such regenerators closed

and the dampers 13 opened, while the gas supply valves of the regenerators at the opposite side of the furnace are opened, the air valves at such side opened and the valves 13 at such side closed, thus placing the furnace in condition for the sweep of the flames in the opposite direction and the discharge of the products of combustion through the regenerators previously employed as heaters.

It will be understood from the foregoing that by providing an air valve and stack valve for each regenerator chamber and co-operating burner flue, separate communication is established between the atmosphere and the stack and such flue independent of any other flue or flues, and accordingly the burner of each burner flue when in operation will be supplied with a proper proportion of air uniformly and regularly fed thereto. Also when any flue burner is in operation communication between the same and the stack will be positively cut off, preventing any undue variations or fluctuations in the flow of air thereto. Any burner also may be entirely cut out of action, without interfering with any of the other burners of the same series, and the air inlet 12 leading thereto may be closed, thus preventing the passage of cold air upwardly through the associated checkers 5 and across the furnace chamber to the checkers at the opposite side, thereby preventing cooling of the checkers and chilling of the glass in the furnace. The quantity of gas supplied to each working burner may also be regulated, to govern the amount of area of the flame projected by the different burners of a series as required, without causing any irregularities in the supply of air to any burner due to the cutting out or variation of flow of gas to another burner or burners, as a result of which the teaser or attendant may control the burners at the working side of the furnace to vary the amount of heat supplied at any point within the area of the heating zone of the burners in a reliable and efficient manner to control the temperature to best suit any working condition.

In Figures 4 and 5 of the drawings I have shown a modified form of my invention in which the construction is generally the same as that shown in Figures 1 to 3, inclusive, except that I dispense with the use of the side tunnels 8 and single stack 10 common to all the regenerators and employ in lieu thereof a separate stack for each regenerator. This separate stack 28 communicates directly with the outer end of the flue 7. The operation with this construction will be readily understood.

Having thus fully described my invention, I claim:

1. In a regenerative glass furnace, a melting chamber, a regenerator having an upper

horizontal flue communicating at its inner end with the melting chamber, a vertical flue communicating at its upper end with the outer end of said upper horizontal flue, a lower horizontal flue communicating at its inner end with the lower end of said vertical flue, a checkerwork barrier in the vertical flue, a passage for intake of air and discharge of products of combustion communicating with the outer end of the lower horizontal flue, the said lower horizontal flue having an upper horizontal wall portion lying between the vertical flue and passage and provided with an air inlet opening and a guideway, a pivotally mounted, vertically movable, gravity closing valve for governing said opening, a vertically movable, gravity closing valve 80 slideable in said guideway and movable into and out of the lower horizontal flue for controlling communication between the same and the said passage, a revoluble shaft supported above said horizontal wall portion of said lower horizontal flue, a pulley mounted on said shaft, a cable intermediately wound on said pulley and having the ends thereof 90 respectively connected with the valves, and means on said shaft for turning the same in one direction or the other for opening either valve and simultaneously closing the other valve.

2. In a regenerative glass furnace, a melting chamber, a regenerator having an upper horizontal flue communicating at its inner end with the melting chamber, a vertical flue communicating at its upper end with the outer end of said upper horizontal flue, a lower horizontal flue communicating at its inner end with the lower end of said vertical flue, a checkerwork barrier in the vertical flue, a passage for intake of air and discharge of products of combustion communicating with the outer end of the lower horizontal flue, the said lower horizontal flue having an upper horizontal wall portion lying between the vertical flue and passage and provided with an air inlet opening and a guideway, a pivotally mounted, vertically movable, gravity closing valve for governing said opening, a vertically movable, gravity closing valve 100 slideable in said guideway and movable into and out of the lower horizontal flue for controlling communication between the same and the passage, a revoluble shaft supported above said horizontal wall portion of said lower horizontal flue, a pulley mounted on said shaft, a cable intermediately wound on said pulley and having the ends thereof 110 respectively connected with the valves, a handle for turning the shaft in one direction or the other for opening either valve and simultaneously closing the other valve, a locking member on said shaft, and a cooperating locking member engageable therewith for holding the shaft against rotation.

3. A glass melting furnace having a plu-

rality of flame and exhaust flues at each side thereof, a burner in each flame and exhaust flue, a plurality of regenerating chambers at each side of the furnace, one for each flame and exhaust flue, and communicating at its top with such flue, a U-shaped tunnel extending around the rear and sides of the furnace and communicating at its rear with a stack, a horizontal flue leading from the base of each regenerating chamber to the adjacent side of the tunnel, each horizontal base flue having an upper wall provided with an air intake opening, a valve controlling the air intake opening of each horizontal base flue, a valve for controlling and cutting off communication between each horizontal base flue and the side of the tunnel with which it connects, a rock shaft above each horizontal base flue, connections between each rock shaft and the air-intake and cut-off valves of the underlying horizontal base flue for simultaneously opening the air-intake valve and closing the controlling and cut-off valve

or vice versa through opposite motions of said shaft, and means applied to each rock shaft for actuating the same.

4. A glass melting furnace having a flame and exhaust flue at each side thereof, a burner associated with each flame and exhaust flue, a regenerating chamber at each side of the furnace, one for each flame and exhaust flue, a horizontal flue leading from the base of each regenerating chamber and having an air intake opening, a stack tunnel with which each horizontal base flue communicates, a valve controlling the air intake opening of each horizontal base flue, a valve for controlling and cutting off communication between each horizontal base flue and the stack tunnel with which it connects, and means for opening either valve and simultaneously therewith closing the other valve of the pair of valves associated with each horizontal base flue.

In testimony whereof I affix my signature.
WILLIAM WESTBURY.
